UNITED STATES PATENT OFFICE

KURT E. BEISSBARTH, OF NEW YORK, N. Y.

SHAVING BRUSH

Application filed September 19, 1927, Serial No. 220,434. Renewed March 13, 1929.

The present invention relates to improvements in shaving brushes and has for its principal object to provide a brush which is constructed of such material as to permit the brush to be discarded after a single use.

One of the important objects of the present invention is to provide a shaving brush which is formed of destructible material and which is adapted for use in public tonsorial parlors whereby each person may have the benefit of a new brush while undergoing shaving or a massage treatment, thus promoting sanitation and preventing the collection of germs on the brush where the same is used more than once as is now customary.

Another important object of the invention is to provide a shaving brush or massage cream applicator which is preferably constructed of cardboard material, the brush being originally cut from a blank and disposed in a flat condition so that the same will not occupy any considerable amount of space, the brush being readily adapted to be folded in such manner as to form a pair of coacting handles on the opposite sides of the brush head when the brush is to be used.

A still further object is to provide an article of manufacture of the above mentioned character which is simple in construction, inexpensive, strong and durable and further well adapted to the purposes for which it is designed.

Other objects and advantages will become apparent during the course of the following description when taken in connection with the accompanying drawing.

In the accompanying drawing forming a part of this application and in which like numerals indicate like parts throughout the same:

Figure 1 is a side elevation of the brush showing the same in its assembled position for use.

Figure 2 is a similar view taken at right angles to Figure 1.

Figure 3 is a top plan view of the blank from which the brush is formed, and

Figure 4 is a sectional view taken substantially on the line 4-4 of Figure 1.

In the drawing wherein for the purpose of

illustration is shown the preferred embodiment of my invention, the numeral 1 designates generally the blank of the brush, the same being cut from a piece of cardboard, although it is to be understood that any other inexpensive pliable material may be used. The blank is cut to form a central circular portion 2 which comprises the brush head and as is clearly illustrated in Figure 4, this circular portion is formed with a series of outwardly stamped protuberances 3 which are formed by suitable dies (not shown) and which protuberances comprise the bristles of the brush head for working up a lather when the brush is used for shaving purposes and to further apply massaging cream when used as an applicator. The protuberances are preferably formed outwardly of the central portion of the circular disc 2 and this central portion of the disc is pressed inwardly to form a relatively large indenture 4 in order to create the necessary suction when the brush is in use.

Extending from the edges of this circular disc 2 at diametrically opposite points are the relatively wide elongated strips 5 and 6 respectively, the outer free ends of these strips being enlarged as illustrated at 7 with reference more particularly to Figures 2 and 3 of the drawing.

In its manufacture, the brush is in the form of the blank shown in Figure 3 with the protuberances and indenture formed in the disc portion 2, and in this manner, the blank can be easily packed for shipping and storing purposes without occupying any considerable amount of space. In assembling the brush for use, the strips 5 and 6 are folded along the lines 8 and 9, respectively, at the juncture with the body portion 2 and the strips are bent upwardly in converging relation as illustrated in Figure 1. The strips are then bent along the lines 10 and 11, respectively, so that the handle forming portion at the free ends of the strips will be disposed in substantially parallel relation and when the strips are so arranged, the free ends thereof will form handle portions to facilitate proper gripping of the brush.

The paper shaving brush when formed in

the manner as shown and above described, will permit the shaving cream or massage cream to be properly applied to the skin in a positive and efficient manner and after the 5 brush has served its purpose, the same is to be discarded. By reason of the fact that the brush is constructed of paper, the same is rendered very inexpensive, and the use of such a brush is very desirable in tonsorial parlors 10 employing the most sanitary methods, and there will not be much expense incurred in the use of such a type of brush.

By constructing the destructible brush from cardboard, sufficient rigidity is provided for 15 permitting the proper use of the brush in applying the cream or lotion to the skin and furthermore the brush of this character will not injure the skin.

While I have shown the preferred embodiment 20 of my invention, it is to be understood that various changes in the size, shape and arrangement of parts may be resorted to, without departing from the spirit of the invention and the scope of the appended claims.

25 Having thus described the invention, what I claim as new and desire to secure by Letters Patent is:—

1. In an applicator of the class described, a brush head formed of cardboard material, a 30 series of protuberances stamped outwardly from the cardboard brush head, said brush head being formed with a central inwardly pressed suction forming indenture, and handle forming strips extending from the opposite 35 sides of the brush head.

2. In an applicator of the class described formed from a blank of cardboard material and including a disc-like body portion having a central inwardly pressed indenture, and outwardly 40 stamped protuberances arranged around said indenture to provide a brush head, elongated handle forming strips extending from the edges of the disc like body at diametrically opposite points and adapted to be bent upwardly at their juncture with the disc like body, said strips being disposed upwardly in converging relation, the free end of each strip being enlarged, said enlarged free ends being disposed in parallel relation to form a 45 handle portion for the brush head.

In testimony whereof I affix my signature.
KURT E. BEISSBARTH.
